Inventor
Albert D. Holden,

By *Clarence O'Brien*,
Attorney

UNITED STATES PATENT OFFICE

ALBERT DAWSON HOLDEN, OF TEXON, TEXAS

GOLF TEE

Application filed March 26, 1930. Serial No. 439,163.

This invention relates to golf tees, and an object of the invention is to provide a golf tee formed of strands of hair or fiber bound together so as to offer the least resistance to the end of a golf stick when driving a ball from the tee of the present invention.

Another object of the invention is to provide a tee of the character referred to that adds practically no weight and no resistance to the downward flight of the club therefore the margin of deflection is so small that if a club were to strike the tee, it would not deviate in the least from its natural course.

Further objects of the invention are to provide a golf tee of the character referred to that is strong, compact and durable, thoroughly reliable for its intended purpose, providing the maximum of strength with the minimum of weight and resistance, that is very simple in its method of assembly and comparatively inexpensive to manufacture.

With the foregoing and other objects in view, the invention consists of a novel construction, combination and arrangement of parts, as will be hereinafter more specifically described and illustrated in the accompanying drawings, wherein is disclosed an embodiment of the invention, but it is to be understood that changes, variations, and modifications may be resorted to without departing from the spirit of the claims hereto appended.

In the drawings wherein like reference characters denote like parts throughout the several views:

Figure 1 is a side elevation of the golf tee in accordance with the present invention,

Fig. 2 is a top plan view thereof.

Referring to the drawings, wherein for the purpose of illustration is shown the preferred embodiment of my invention, 3 indicates generally the body portion of the tee in accordance with the present invention. The body portion is formed of a cylindrical stack of individual hair or fiber strands bound together intermediate their ends and at substantially a right angle to the extent of the strand, by a band 4 formed of silk or flax thread.

The band 4 is covered with shellac to protect the silk or flax thread against the weather

and wear. The band of threads 4 causes a pressure and compression intermediate the ends of the stack of strands, which causes the sides of the body 3 to incline outwardly from the band 4 in opposite directions to the ends of the body.

The top and bottom faces of the body 3 are cupped as at 5, 6 to provide pockets for the golf ball 7 at either end of the body. The band 4 anchors the individual strands of hair or fiber together, in immovable relation and the flared upper and lower ends of the body provides broad surfaces, one to accommodate the golf ball, and the other to form a pedestal or base to rest upon the ground 8.

While the body portion of the tee may be formed of hair or fiber, it is within the contemplation thereof to form the body of a mixture of hair and fiber strands.

The body portion is of individual strands, and forms a golf tee that is very light, but yet is strong enough to support the weight of a golf ball under all conditions. The golf tee in accordance with the present invention does not have to be stuck in the ground and either end is suitable for a teeing surface according to which end hits first. The tee will travel only a few inches after being struck with the club.

Furthermore, the tee may be made in various heights to suit the desire of various golfers.

It is thought that the embodiment of the invention has been disclosed in considerable detail merely for the purpose of exemplification, since in actual practice it attains the features of advantage enumerated as desirable in the statement of the invention and the above description.

It is to be understood that by describing in detail herein any particular form, structure or arrangement, it is not intended to limit the invention beyond the terms of the several claims or the requirements of the prior art.

Having thus described my invention, what I claim as new is:

1. A golf tee comprising an elongated fibrous body, said body cupped at its top and bottom, and means intermediate the ends of

the body for anchoring the fibers in immovable relation to each other.

- 5 2. A golf tee comprising an elongated fibrous body, said body cupped at its top and bottom, means intermediate the ends of the body for anchoring the fibers in immovable relation to each other, said fibrous body including a stack of fibers disposed side by side in upstanding relation.
- 10 3. A golf tee comprising an elongated fibrous body, said body cupped at its top and bottom, means intermediate the ends of the body for anchoring the fibers in immovable relation to each other, said fibrous body including a stack of fibers disposed side by side in upstanding relation, said means consisting of a thread wrapped about the bristles at an angle to the lineal extent of the fibers.
- 15 4. A golf tee comprising an elongated fibrous body, said body formed of a stack of individual strands of fibrous material, and means intermediate the ends of the stack for binding the stack into a unit.
- 20 5. A golf tee comprising an elongated body formed of a bundle of individual strands of fibrous material, and the strands of the bundles bound together intermediate their ends by a band.
- 25 6. A golf tee comprising an elongated body formed of a bundle of individual strands of fibrous material, a band disposed about the bundle intermediate the ends thereof to anchor the strands together and compress the body so that the sides flare outwardly to the opposite ends thereof, and the opposite ends of said body being cupped.

In testimony whereof I affix my signature.
ALBERT DAWSON HOLDEN.
